METHOD OF MAKING JAR CLOSURES

Walter Kowal, New York, N. Y., assignor to
 Phoenix Metal Cap Company, Inc., Chicago,
 Ill., a corporation of New York

Application July 31, 1936, Serial No. 93,706

3 Claims. (Cl. 113—121)

This invention relates to a new and improved method of making jar closures, its chief utility being in connection with caps of the double shell type.

- 5 Heretofore, in the manufacture of metal caps of this type, it has been the usual practice to shape the inner shell from a circular blank, curl the edge thereof and then assemble the inner shell inside of the outer one.
- 10 In die-cutting the circular blanks, it is generally considered the best practice to use a layout of regularly spaced circles, with a definite "bridge" between adjacent blanks to permit the punches to cut them and to leave the scrap in one piece for convenience in handling and to be sure that no loose chips are permitted to fall into the die.
- 15

The sheet is usually first cut into strips for a single row layout or for staggered rows in a double or triple die layout. Not only does the circular shape of the blank entail a considerable percentage of waste metal, but the smooth contour of the inner shell sometimes allows independent turning of the outer shell thereon, even though the inner shell is roughened before assembly.

With the above facts in mind, it is an object of this invention to make the inner shell of such form that independent turning will be definitely prevented.

A further object of the invention is to cut the blanks in such a manner that there is a definitely smaller percentage of waste metal than is possible when the blanks are cut in the shape of a circle.

In manufacturing caps according to this invention, therefore, the inner shell blank is cut so that its periphery consists of a number of straight sides or chords connected by arcs, the diameter of the latter being the same as that of the normal circular blank cut according to the usual practice. In other words, the inner shell blank is cut in the form of a polygon with the corners thereof rounded to form arcs. When such a blank is stamped and curled, these corners form spaced projections or beads around the edge of the shell, and after it is assembled within the outer shell, these projections serve as keys to lock the two shells against independent turning with respect to each other.

Obviously, the cutting of a blank with four or six oppositely disposed sides permits a layout which effects an important saving in material and the corners of arcuate segments between these

sides affords the material to form the locking projections above mentioned.

The invention will be more particularly described with reference to the accompanying drawing, in which:

Fig. 1 shows a suitable layout from which the blanks may be cut with a considerable saving of material.

Fig. 2 is a plan view of a suitably shaped blank for the inner shell of a cap construction in accordance with the invention.

Fig. 3 is a top plan view of a shell drawn from the blank shown in Fig. 1.

Fig. 4 is a side view in section of Fig. 3.

Fig. 5 is a top plan view of the shell after the edge has been curled.

Fig. 6 is a side view in section of Fig. 5.

Fig. 7 is a bottom plan view of the completed cap after the outer shell has been secured thereto.

Fig. 8 is a side view in section of Fig. 7.

In the present embodiment of the invention, the inner shell blank is formed with six equally spaced straight sides or chords 10, as shown in Figure 2, and differs in shape from a regular hexagon in that the corners are rounded to form concentric arcs 11. The blank is then drawn, as shown in Figures 3 and 4, to form a crown 12 with the arcs forming spaced brim portions 13. These brim portions are then curled to form a series of beads, as shown at 14 in Figures 5 and 6, and the panel 20 is raised from the crown 12. The side wall of the crown 12 is formed with a screw thread 15, and may or may not be knurled. The inner shell thus formed is then assembled within the outer shell 17, as shown in Figure 8, with the raised panel 20 and the edge 21 in contact with the top of the outer shell, and the edge 18 of the outer shell is curled about the curled edge of the inner shell including the spaced beads 14. Thus the beads 14 constitute keys to prevent independent turning of one shell with respect to the other.

In cutting blanks for metal caps, it is generally recognized that the best practice is to cut the metal into strips from which the blanks are punched. The layout leaves a definite "bridge", usually about 1/16 inch, between adjacent blanks to permit punches to cut the blanks and leave the scrap in one piece for convenience in handling, and to be sure that no loose chips are permitted to fall into the die.

For cutting the six-sided inner shell blanks described above, it is preferred to use the triple die staggered layout shown in Figure 1. Here the blanks are in staggered relation, with the

5 straight sides 10 of adjacent blanks parallel to each other and separated by a "bridge" 19. In the layout for cutting circular blanks, as heretofore used for the inner shells, the distance between the centers of adjacent blanks must not be less than twice the radius of the blank plus the width of the bridge between them, whereas in this layout for the same sized caps, the distance between centers of adjacent blanks is equal to twice the apothem of the blank plus the width of the bridge 19. This permits considerable reduction 10 in both the width and the length of the strip from which a given number of the blanks are to be cut, with a corresponding saving in material.

15 From the foregoing description, therefore, it will be apparent that the formation of the inner shell blank with the straight sides 10 joined by the arcuate portions 11 not only provides keys to prevent independent turning, but also permits a layout for die-cutting of the blanks which results in an appreciable saving of material. A similar saving of material may be effected if a single or double row layout is used.

20 Similar results may also be obtained, both in providing locking means to prevent independent turning and in saving material, if the blanks are formed with four straight sides, or indeed with any even number of sides, with arcuate segments between them.

25 30 While I have shown and described in detail several specific embodiments of the invention, it is to be understood that this is merely for the purpose of illustration and that the invention also embraces such other modifications as may fall within the scope of the appended claims.

35 Having thus described the invention, what I claim as new and desire to secure by Letters Patent, is:

1. The method of producing inner shells for

5 double shell caps which are adapted to fit over an inner shell, which method consists in cutting from a metal sheet a plurality of non-circular blanks having relatively long straight sides joined by relatively short sides with the relatively long 10 straight sides of each blank parallel to an adjacent long side of an adjacent blank in the metal sheet, shaping each blank into cup form, curling the relatively short sides to provide lugs, and threading the depending wall portion of each cup- 10 shaped blank.

2. The method of producing inner shells for double shell caps which are adapted to fit over an inner shell, which method consists in cutting from a metal sheet a plurality of non-circular blanks 15 having relatively long straight sides joined by relatively short sides in the form of arcs with the relatively long straight sides of each blank parallel to an adjacent long side of an adjacent blank in the metal sheet, shaping each blank into 20 cup form, curling the relatively short sides to provide lugs, and threading the depending wall portion of each cup-shaped blank.

3. The method of producing inner shells for double shell caps which are adapted to fit over an 25 inner shell, which method consists in cutting from a metal sheet a plurality of non-circular blanks having relatively long straight sides joined by relatively short sides with the relatively long 30 straight sides of each blank parallel to an adjacent long side of an adjacent blank in the metal sheet, shaping each blank into cup form, curling the relatively short sides so as to leave a continuous and smooth surface around the bottom peripheral edge of each cup-shaped blank and so 35 as to provide lugs, and threading the depending wall portion of each cup-shaped blank above the lugs formed by the curled short sides.

WALTER KOWAL.
